MINTING MACHINE

Original Filed April 30, 1918

Charles B. Officer.

UNITED STATES PATENT OFFICE.

CHARLES B. OFFICER, OF WINNETKA, ILLINOIS, ASSIGNOR TO SULLIVAN MACHINERY COMPANY, A CORPORATION OF MASSACHUSETTS.

MINING MACHINE.

Application filed April 30, 1918, Serial No. 231,698. Renewed January 13, 1925.

This invention relates to mining machines, especially those of the type fed along the face in which the cut is made, and has more particular reference to the feeding mechanism of machines of this type.

In such machines it is customary to include, in the transmission mechanism for actuating the feeding means, a yielding element or friction device adapted to yield in case the resistance to movement of the machine becomes excessive, thereby preventing breakage of the parts. It is also customary, when such a friction device is employed, and particularly in machines having provision for different feeding speeds, to provide means for "loading" the friction device, i. e., for increasing the resistance to yielding or slipping opposed thereby, inasmuch as a greater resistance or friction may safely and advantageously be permitted when the mechanism is adjusted to produce a relatively fast feed than when adjusted for a slow feed. Such friction loading means have usually been entirely under the control of the operator, both as to the amount of the additional resistance and the condition under which it may be interposed, thereby making it possible for the operator, either wilfully or accidentally, to overload the friction to an unsafe extent or under improper conditions.

The present invention has for its general object to provide feeding mechanism for machines of this character wherein danger of injury to the mechanism, due to improper loading of the friction, is avoided. To this end the invention contemplates the provision of means whereby the total amount of effective resistance to yielding which the operator is able to interpose in the mechanism is limited to a predetermined maximum, so that, even when the friction has been loaded by the operator to the full extent possible, the mechanism is still capable of yielding under conditions of abnormal stress before danger of breakage is reached. This object of the invention may be accomplished in a number of ways, but as herein shown means are provided for automatically loading the friction a predetermined amount when released by restraining devices under the control of the operator. The invention further contemplates the provision, in a mining ma-

chine having reversible feeding mechanism operable to produce relatively fast and slow speeds and including a friction device or its equivalent, of improved coordinated means for controlling the feeding speed, for reversing the direction of feed, and for loading the friction device, said means being of such a character as to make it impossible to load the friction when the mechanism is adjusted for slow speed or to change the direction of feed when the friction is loaded.

The foregoing and other objects of the invention, together with means whereby the same may be carried into effect, will best be understood from the following description of one form or embodiment thereof shown for purposes of illustration in the accompanying drawings.

In said drawings,

Fig. 1 is a plan view partly broken away.
Fig. 2 is a section on the line 2—2 of Fig. 1.

Fig. 3 is a detail perspective view of the friction loading lever.

Fig. 4 is a detail sectional view on line 4—4 of Fig. 1.

Fig. 5 is an enlarged detail view of the interlocking mechanism for the controlling mechanism shown in Fig. 1.

The invention is herein shown as embodied in a mining machine of the familiar room and pillar type, said machine comprising, in general, a cutter chain 10 carried by a cutter bar 11 projecting from a body including a motor casing 12 and a gear or transmission casing 13. The machine as a whole is fed along the face in which the cut is made by means of feeding mechanism comprising a feed chain 14 anchored at its ends by suitable jacks or other securing devices (not shown), said chain passing over guide sprockets or rollers 15, 16, and 17, on the machine body and cooperating with a feed sprocket 18, also on the machine body and actuated through suitable transmission mechanism, hereinafter referred to, from the motor (not shown) in the casing 12. The parts thus far referred to as to their general organization and function, are well known in the art and, except as to certain features herein-after referred to, require no further description.

A gear 19 is herein shown to be driven through suitable connections (not shown) from the motor in the casing 12, said gear having a hub 20 journaled in a bearing 26 carried by a suitable framework 24 in the casing 13. The hub 20 is splined to a shaft 21 journaled in suitable bearings 22 and 23, supported, respectively, by the framework 24 and by a cap piece 25 secured to said framework. Mounted on the shaft 21 for rotation therewith, is a pinion 27 which actuates suitable mechanism (not fully shown herein but well known in machines of this general character) for driving the cutter 10 chain 10.

Loosely mounted on the shaft 21 is a clutch member 28 having an internal clutch face engaged by friction clutch members or shoes 29 connected by toggle links 30 with a clutch controller 31 having a splined connection with the shaft 21, said parts constituting a well known form of friction device. Movement of the controller 31 toward the member 28 causes the toggle links 30 to force the shoes 29 outwardly against the clutch face of the member 28, thereby frictionally connecting said member to the shaft 21. The controlling member 31 is normally pressed toward the clutch member 28 by means of a spring 32 bearing at one end against an interior shoulder on the member 31 and at its opposite end against a nut 33 on the threaded end of the shaft 21, whereby the tension of said spring may be adjusted. In the operation of the device, the member 28 is caused normally to rotate with the shaft 21 but is permitted to yield or slip on said shaft should an unusual resistance be encountered. The resistance opposed by said device against such yielding or slipping is determined by the force with which the member 31 is pressed toward the member 28 by the spring 32 or by other means herein-after referred to.

The hub member 28 is formed with a pinion 34 which meshes with a gear 35 rotatably mounted on a carrier 36 having an annular portion movably mounted in a circular guide on the upper face of the cap piece 25 concentric with the shaft 21. The gear 35 meshes with a gear 37, also rotatably mounted in the carrier 36, said carrier being angularly movable in its guide in the cap piece 25 to cause either of the gears 35 or 37 to engage and rotate a gear 38, thereby causing said gear to be rotated in one direction or the other according to the adjustment of the carrier 36.

For shifting the carrier 36 to cause the gear 38 to be driven directly in one direction by the gear 35, or in the opposite direction through the gears 35 and 37, said carrier is connected by a link 39 with a longitudinally movable rod or rock shaft 40 mounted for longitudinal and angular move-

ment in suitable bearings in the casing 13 and provided at its rear end with an operating handle 41 whereby said rod or shaft may be moved longitudinally to cause the shifting of the carrier 36 in its guide.

The gear 38 constitutes a member of a transmission mechanism for rotating the feed sprocket 18. Such transmission mechanism specifically forms no portion of the present invention and, being well known in the art, is not shown nor described in detail herein, it being sufficient to say that said mechanism preferably includes selective, multiple speed gearing for producing relatively fast and slow speeds of rotation of the sprocket 18, and, consequently, fast and slow feeding speeds, said gearing being controlled by usual clutch mechanism indicated in dotted lines in Fig. 1 and operable through a suitable manually operated adjusting device or lever 42. As shown in Fig. 1, the lever 42 is in a position to produce a relatively slow feeding speed but may be turned through an angle of approximately 180° to the position indicated in dotted lines, to produce a relatively fast feed.

Rotatably mounted on the clutch controlling member 31, as by an antifriction bearing 43, is a ring or collar 44 having trunnions to which are pivoted arms 45 on a friction loading lever or rocker 46, said lever or rocker being rotatably mounted on the rock shaft 40 and having a third arm 47. Interposed between the arm 47 and a fixed portion of the frame 24, is a spring 48, said spring engaging a follower 49 carried by an adjusting screw 50 in threaded engagement with the arm 47, whereby the tension of said spring may be adjusted. The spring 48 acts through the lever 46 to press downwardly upon the ring 44, thereby supplementing the action of the spring 32 and causing the shoes 29 to engage the clutch surface of the member 28 with an increased pressure, the amount of additional pressure being determined by the adjustment of said spring 48. The lever 46 is normally held inoperative, against the tension of the spring 48, by means of lugs 51 on collars 52 secured to the rock shaft 40, said lugs 51 engaging lugs 53 on the arms 45 of the lever 46. The rock shaft 40 is provided at its rear end with a hand lever 54, preferably formed integral with the handle 41. By lifting up on the hand lever 54, the shaft 40 may be turned, thereby carrying the lugs 51 out of engagement with the lugs 53 and permitting the spring 48 to operate the lever 46 to load the friction device as above explained. It will be observed that lifting of the lever 54 does not directly operate to load the friction device to an extent determined by the force applied to said lever, but merely removes the restraining means for the friction loading device, which thereafter becomes auto-

125
130

matically operative to load said device to a predetermined extent.

For purposes of safety, it is desirable that loading of the friction be prevented when the mechanism is adjusted to produce slow feed, and to this end an interlock is provided between the levers 42 and 54, said interlock comprising an extension 55 on the lever 54 which overlies an extended portion 56 on the lever 42, whereby when said lever 42 is in the position to adjust the transmission mechanism for a slow feed, as shown in Fig. 1, said extension 55, by engaging the extension 55, will prevent manipulation of the lever 54 to release the friction loading means. Attention is also directed to the fact that the extended portion 56 on the lever 42 is slotted between its ends as shown in Figs. 1 and 5 in such a manner as, by the engagement of the left hand wall of the slot (Fig. 5) with the extension 55, to prevent the handle 42 from being swung from slow to fast feed position unless the member 54 is moved to release the friction, i. e. pushed down in such a manner as to cause its end 55 to clear the left hand wall of the slot in the member 56.

Similarly, it is desirable that means be provided for preventing shifting of the reversing gearing when the friction is loaded, and to this end locking means are provided for preventing longitudinal movement of the rod or shaft 40 when said shaft is in an angular position to permit loading of the friction. Said means comprises a fixed stop or lug 57 projecting from the machine frame, said lug cooperating with the extension 55 on the lever 54. When said lever 54 is in a position to permit operation of the friction loading means, the extension 55 thereon engages one side or the other of the lug 57, thereby preventing longitudinal movement of the shaft 40 to shift the reversing gearing. When, however, the lever 54 is in a position to cause the lugs 51 to engage the lugs 53 and hold the friction loading lever 46 inoperative, the shaft 40 may be moved longitudinally by the handle 41, the extension 55 at this time passing over the lug 57.

While I have in this application specifically described one embodiment which my invention may assume in practice, it will be understood that this form of the same is shown for purposes of illustration and that my invention may be modified and embodied in various other forms without departing from its spirit or the scope of the appended claims.

What I claim as new and desire to secure by Letters Patent is:

1. In a mining machine, the combination with feeding mechanism including a friction device, of a lever connected with said friction device, a spring acting through said lever to increase the friction of said device,

a rock shaft on which said lever is loosely mounted, and means on said rock shaft for holding said lever inoperative.

2. In a mining machine, the combination with feeding mechanism including a friction device, of loading means for said friction device comprising a rock shaft, a lever loosely mounted on said rock shaft, said lever having a pair of arms connected with said friction device and provided with laterally projecting lugs and a third arm, a spring engaging said third arm and acting through said lever to increase the friction of said friction device, and lugs on said shaft adapted to engage said first named lugs to hold said lever inoperative against the tension of said spring.

3. In a mining machine, the combination with feeding mechanism including a friction device, of a lever connected with said friction device, a spring acting through said lever to increase the friction of said device, a rock shaft on which said lever is loosely mounted, means on said rock shaft for holding said lever inoperative against the tension of said spring, and a hand lever on said rock shaft for turning the same.

4. In a mining machine, the combination with feeding mechanism including a yielding element, of reversing means for said feeding mechanism, a longitudinally movable rod and connections for operating said reversing means, means for increasing the resistance to yielding opposed by said element, and means for operating said last named means and for locking said rod when said resistance increasing means is operative.

5. In a mining machine, the combination with feeding mechanism operable to produce relatively fast and slow feeding speeds and including a yielding element, of reversing means for said feeding mechanism, a longitudinally movable rod and connections for operating said reversing means, means automatically operative to increase the resistance to yielding opposed by said element, and cooperating mechanism for controlling the feeding speed, for restraining said resistance increasing means, and for locking said rod when said resistance increasing means is operative.

6. In a mining machine, the combination with feeding mechanism operable to produce relatively fast and slow feeding speeds, and including a yielding element, of a longitudinally movable rod, reversing means for said feeding mechanism operated by longitudinal movement of said rod, means controlled by said rod for increasing the resistance to yielding opposed by said element, means for controlling the feeding speed and for locking said rod against movement to increase the resistance of said element when the mechanism is adjusted for slow speed, and means for locking said rod against lon-

gitudinal movement when said resistance increasing means is operative.

7. In a mining machine, the combination with feeding mechanism including a yielding element, a longitudinally movable rock shaft, reversing means for said feeding mechanism operated by longitudinal movement of said rock shaft, means for increasing the resistance to yielding opposed by said element, said last named means being controlled by angular movement of said rock shaft, and means for locking said rock shaft against longitudinal movement when in an angular position to render said resistance increasing means operative.

8. In a mining machine, the combination with feeding mechanism including a yielding element, of a longitudinally movable rock shaft, reversing means for said feeding mechanism operated by longitudinal movement of said rock shaft, means for increasing the resistance to yielding opposed by said element, said last named means being controlled by angular movement of said rock shaft, a lever for turning said rock shaft, and a fixed stop engaged by said lever when in an angular position to render said resistance increasing means operative to lock said shaft against longitudinal movement.

9. In a mining machine, the combination with feeding mechanism operable to produce relatively fast and slow feeding speeds and including a yielding element, of a longitudinally movable rock shaft, reversing means for said feeding mechanism operated by longitudinal movement of said rock shaft, means automatically operative to increase the resistance to yielding opposed by said element, means for restraining said last named means, said restraining means being operated by angular movement of said rock shaft, a lever for turning said rock shaft, a lever and connections for controlling the feeding speeds, said last named lever having means for locking said first named lever when the mechanism is adjusted for slow speed, and a fixed stop engaged by said first named lever when in an angular position to render said restraining means inoperative to lock said shaft against longitudinal movement.

10. In a mining machine, the combination with feeding mechanism including a friction device, of reversing means for said feeding mechanism, a longitudinally movable rod and connections for operating said reversing means, means for loading said friction device, a member for controlling said loading means, and means cooperating with said controlling member for locking said rod.

11. In a mining machine, the combination with feeding mechanism including a friction device, of a longitudinally movable

rock shaft, reversing means for said feeding mechanism operated by longitudinal movement of said rock shaft, a lever loosely mounted on said rock shaft and connected with said friction device, a spring acting through said lever to load said friction device, means on said rock shaft and rendered operative by angular movement thereof for holding said lever inoperative, a lever for turning said rock shaft, and a fixed stop engaged by said last named lever when in a position to permit operation of said first named lever, said stop acting to lock said shaft against longitudinal movement.

12. In a mining machine, the combination with feeding mechanism including a yielding element, of reversing means for said feeding mechanism, means for controlling the resistance to yielding opposed by said element, and a common operating device for said reversing means and resistance controlling means.

13. In a mining machine, the combination with feeding mechanism including a yielding element, of a longitudinally movable rock shaft, reversing means for said feeding mechanism operated by longitudinal movement of said rock shaft, and means for increasing the resistance to yielding opposed by said element, said last named means being controlled by angular movement of said rock shaft.

14. In a mining machine, the combination with feeding mechanism operable to produce relatively fast and slow feeding speeds and including a yielding element, of reversing means for said feeding mechanism, means for controlling the resistance to yielding opposed by said element, a common operating device for said reversing means and resistance controlling means, and a second operating device for controlling said first named operating device and the feeding speed.

15. In a mining machine, the combination with feeding mechanism including a yielding element, of reversing means for said feeding mechanism, means for increasing the resistance to yielding opposed by said element, and a common controlling device for said reversing means and resistance increasing means, said device being locked against movement to operate said reversing means when in a position to cause increase of said resistance.

16. In a mining machine, the combination with feeding mechanism including a friction device, of reversing means for said feeding mechanism, means for loading said friction device, and a common controlling member for said reversing means and loading means.

In testimony whereof I affix my signature.

CHARLES B. OFFICER.
